UNITED STATES PATENT OFFICE.

JAMES H. POAGE, OF CHICAGO, ILLINOIS.

PROPELLING ENGINE OR MOTOR.

1,078,748.

Specification of Letters Patent. Patented Nov. 18, 1913.

Application filed December 19, 1912. Serial No. 737,687.

To all whom it may concern:

Be it known that I, JAMES H. POAGE, citizen of the United States, residing at Chicago, in the county of Cook and State of Illinois, have invented a certain new and useful Improvement in Propelling Engines or Motors, of which the following is a full, clear, concise, and exact description, reference being had to the accompanying drawings, forming a part of this specification.

My invention relates to boat propelling equipment and finds its preferred embodiment in connection with motors that are in the form of hydro-carbon engines, though the features thereof may be embodied in association with other forms of motors as will be apparent from the description to be given.

One feature of my invention resides in the provision of improved means whereby a motor driven propeller may be bodily shifted through an angle of 180° to reverse the direction of travel of the boat without reversing the direction of rotation of the propeller. The means for shifting the propeller is preferably so constructed that the propeller may be bodily swung to the right or to the left through an angle of 180° in each swinging movement. Where it is desired merely to swerve the boat, the extent to which the propeller is bodily swung is

suited to the degree to which the boat is to be swerved. In practising this feature of my invention a pinion is in fixed relation with the bearing for the propeller and a handle operated segmental gear is in mesh with the pinion, the arcal reach of the gear being of such extent that the pinion may be turned a half revolution in either direction for the purpose specified, the radius of the segmental gear being sufficiently large so that the swinging of the handle, where grasped, is sufficiently small to make the operation of the handle convenient. The segmental gear and pinion in mesh therewith constitute one form of mechanism for increasing the angular motion of the propeller in its bodily movement with respect to the angular motion of the handle so as conveniently to reduce the swing of the handle as compared with the bodily swing of the propeller.

I am aware that it is old bodily to swing motor driven propellers through the agency

of pinions and segmental gears and also through the agency of two meshing segmental gears but the constructions of the prior art having these characteristics were of such nature that the bodily movement effected for the propellers was limited so that it was possible only to swerve the boat in its forward movement whereas with the equipment of my invention the boat may not only be swerved in its forward movement but may also be caused to move backwardly and swerved in its backward movement.

My invention has other features and will be fully explained by reference to the accompanying drawings showing the preferred embodiment thereof and in which drawing—

Figure 1 is a sectional elevation of an engine or motor driven propeller mechanism equipped in accordance with the invention; Fig. 2 is a rear view of the structure shown in Fig. 1, a tubing portion being broken away to reveal some characteristics of construction; Fig. 3 is a plan view of the mechanism illustrated in Figs. 1 and 2; Fig. 4 is a sectional view on line 4-4 of Fig. 1; and Fig. 5 is a sectional view on line 5-5 of Fig. 1.

Like parts are indicated by similar characters of reference throughout the different figures.

The motor which I preferably employ is in the form of a hydro-carbon engine of any suitable internal construction. The engine is equipped with the usual cylinder 1, reciprocating piston 2 working within the cylinder, a pitman 3 connecting the piston with the crank pin of the crank 4 upon the propeller shaft 5. The fly wheel 6 is fixed upon the upper end of the shaft 5 and a suitable fuel reservoir 7 intervenes between the fly wheel and the engine casing. The engine casing is provided with a downwardly extending sleeve 8 which is preferably formed in the same integral casting with the portion of the engine casing with which the sleeve is directly connected. A similar but upwardly extending sleeve 9 is provided at the upper portion of the engine casing, the sleeves 8 and 9 being co-axial and alining the portions of the shaft 5 that are upon opposite sides of the crank 4, these sleeves thus constituting bearings. The use of inserted bearing metal within the sleeves 8 and 9 is preferably

avoided by forming these sleeves and the portions of the engine casing integral therewith of bearing metal. The propeller 10 has its hub portion fixed with respect to a shaft 5 11 and this shaft is provided with bearings at its ends in a gear housing 12. A miter gear 13 is fixed with respect to the shaft 11, and a miter gear 14 that is in mesh with the miter gear 13 is in fixed relation with a shaft 10 15 that is co-axial with and is driven by the shaft 5. The driving connection between the shafts 15 and 5 includes a sleeve 16 surrounding the lower reduced end of the shaft 5 and connected therewith by a pin 17. The 15 sleeve 16 is provided with a spline 18 engaging a splined slot in the shaft 15. The spline 18 is preferably wedge-shaped in cross section and the splined slot receiving the same is correspondingly shaped, this construction being superior to one in which the spline and splined slot are rectangular in that lost motion between the parts is taken up. The sleeve 8 is downwardly elongated and has apertures 19 (Figs. 1 and 2) to permit of the insertion of the pin 17.

By the construction thus far described the shaft sections 5 and 15 are relatively adjustable longitudinally of their common axis in order properly vertically to position the propeller with respect to the boat. In order that this adjustment may be determined and may be secured when determined I preferably provide a sleeve 20 which is in telescoping relation with and receives the lower end 30 of the bearing sleeve 8, another sleeve 21 receiving the upper end of the sleeve 20 and having a slot 22 at its lower end to constitute the lower portion of the sleeve 21 a clamping member, this portion of the sleeve 21 being 35 contractible by means of a clamping wing nut 23 engaging lugs upon opposite sides of the slot 22. When the bolt 23 is tightened the sleeves 20 and 21 are brought in fixed relation whereby the propeller is held properly 40 vertically spaced from the engine. The sleeve 21 engages a lower or step sleeve bearing 24 fixed by means of a suitable mounting, whose preferred form will later be described, with respect to the stern 25 of the 45 boat. The support 24 holds the sleeve 21 and owing to the clamping engagement between the sleeves 21 and 20 effected at 23 the shaft sections 15 and 8 are held in the relative positions that are determined by the longitudinal 50 movement of the shaft 15 within the sleeve 16, the lower end of the shaft 15 being in fixed relation with the hub of the spur gear 14. The shaft 15 is prevented from dropping owing to the engagement of 55 the spur gear 14 with the spur gear 13 and the fact that the bearing for the spur gear 13 is in fixed relation with respect to the sleeve 20, this bearing being an inwardly extending projection of the housing 12 that

is fixed with respect to the shaft 20. The 65 housing 12 may have an upwardly extending projection 26 which may constitute a bearing sleeve for the lower end of the shaft 15 and which may or may not have its bore faced with special bearing metal as desired. 70 The step bearing sleeve 24 desirably carries radially projecting bolts 27 which extend through arcal slots 28 in bracket arms 29 that project from a bracket frame 30 clamped to the stern or other suitable portion of the boat by means of clamping wing nuts 31. The engine casing has swinging connection at 32 with the bracket frame 30 and the slots 28 are upon circles whose centers are located at the mounting shaft 32. 75 By this construction the propeller 10 and the engine driving the same may together be swung bodily in a vertical plane to determine the proximity of the propeller, whose vertical position has been adjusted, 80 with respect to the boat. After this adjustment has been determined it is secured by means of wing clamping nuts 33.

I will now describe the feature of my invention that enables me to swing the propeller as desired and sufficiently to reverse the travel of the boat, and while this feature of my invention is preferably practised in connection with the construction above specifically described, the present feature of 95 my invention is not to be limited to association with the foregoing construction.

The upper end of the sleeve 21 turns upon the upper portion of the bearing sleeve 8 and is there provided with a pinion 34 fixed 100 with respect thereto. This pinion 34 is in mesh with a segmental gear 35, the center of which is coincident with the mounting for the segmental gear 35 located at 36, this mounting pivotally supporting the segmental gear upon and beneath the casing of the engine. The arcal reach of the pitch curve of the segmental gear is so proportioned with respect to the pitch circle of the pinion that the segmental gear, when swung 105 from its middle position in either direction, is adapted to turn the pinion through an angle of 180°. The segmental gear 35 is provided with a handle 37, the mounting 36 being interposed between the segmental gear 110 and the handle. The radius of the segmental gear and the radius of the pinion are so selected that a given angular movement of the handle 37 will be accompanied by a materially increased angular movement of 115 the pinion 34 and a bodily movement of the propeller 10 similar to the movement of the pinion 34 whereby the range of operation of the handle may be confined to the space between the sides of the boat for the purpose of turning the pinion throughout its maximum movement of 180° in either direction. The pinion 34 being fixed with respect 120

to the sleeve 21 and the sleeve 21 being fixed with respect to the bearing support of the propeller 10 by the construction previously described, any movement imparted to the 5 pinion by the segmental gear engaging the same will be accompanied by a corresponding bodily movement of the propeller 10 so that the direction of the boat may be swerved when the pinion is turned through angles 10 less than 180° and may be completely reversed when the pinion is turned completely through an angle of 180°, and after having been reversed the boat may be swerved in its backward movement but in one general direction 15 consequent upon the turn of the pinion 34 in one direction 180° by suitably swinging the handle. In Fig. 1 a completely reversed position of the propeller is indicated by dotted lines. By mounting the handle 20 at 36 upon the engine or motor casing the handle and segmental gear 35 keep their relative positions with respect to the engine casing as the said casing is adjusted about the bolt at 32 so that the gear 35 and the 25 pinion 34 are maintained properly in mesh. The tube or sleeve that is turned by the operation of the handle for the purpose of turning the propeller shaft housing is contracted at its upper end so as to have limited 30 engagement with the sleeve that constitutes a downward extension of the motor casing so as to improve the operation of the steering and reversing mechanism.

The handle 37 is desirably formed in two 35 sections as illustrated most clearly in Fig. 1, one section being integrally formed with the segmental gear 35 while the other section includes an offset portion 38 that is insertible through an aperture in the companion 40 portion of the handle, this companion portion of the handle thus being interposed between the offset portion 38 and the shank of the handle which extends to the grip 39. The grip section of the handle carries a bolt 45 40 upon which a wing nut 41 turns, the elements 40 and 41 serving to maintain the two sections of the handle together when these sections are assembled.

While I have herein shown and particularly 50 described the preferred embodiment of my invention I do not wish to be limited to the precise details of construction shown as changes may readily be made without departing from the spirit of the invention, but 55 Thus having described my invention I claim as new and desire to secure by Letters Patent the following:—

1. Boat propelling equipment including a propeller; a motor for driving the same; 60 mechanism for bodily reversing the position of the propeller to cause it to reverse the direction in which it is driving a boat; a handle for effecting this adjustment of the propeller; motion increasing means inter-

posed between the handle and propeller to 65 increase the angular bodily movement of the propeller with respect to the angular movement of the handle; a mounting permitting the motor and propeller to be swung; and a mounting for the handle causing the handle to accompany the motor when swung upon its mounting. 70

2. Boat propelling equipment including a propeller; a motor for driving the same; mechanism for bodily reversing the position 75 of the propeller to cause it to reverse the direction in which it is to drive a boat; a handle for effecting this adjustment of the propeller; motion increasing means interposed between the handle and propeller to 80 increase the angular bodily movement of the propeller with respect to the angular movement of the handle, said motion increasing means including a pinion moving with the propeller and a segmental gear meshing 85 with the pinion and moved by the handle; a mounting permitting the motor and propeller to be swung; and a mounting for the handle causing the handle to accompany the motor when swung upon its mounting. 90

3. Boat propelling equipment including a propeller; a motor for driving the same; mechanism for bodily changing the position 95 of the propeller; a handle for effecting this adjustment of the propeller; motion increasing means interposed between the handle and propeller to increase the angular bodily movement of the propeller with respect to the angular movement of the handle; a mounting permitting the motor and propeller to be swung; and a mounting for the 100 handle causing the handle to accompany the motor when swung upon its mounting.

4. Boat propelling equipment including a propeller; a motor for driving the same; 105 mechanism for bodily changing the position of the propeller; a handle for effecting this adjustment of the propeller; motion increasing means interposed between the handle and propeller to increase the angular bodily movement of the propeller with respect to the angular movement of the handle, said motion increasing means including a pinion moving with the propeller and a segmental gear meshing 110 with the pinion and moved by the handle; a mounting permitting the motor and propeller to be swung; and a mounting for the handle causing the handle to accompany the motor when swung upon 115 its mounting.

5. Boat propelling equipment including a propeller; a support for the propeller; a motor provided with a downwardly extending sleeve through which the motor shaft passes, said motor shaft being in driving 125 connection with the propeller; a second sleeve in driving connection with said propeller support and inwardly contracted at

its upper end where it incloses the aforesaid sleeve and there has bearing engagement with said sleeve; and mechanism for turning the second sleeve upon the first thereby to turn the propeller support and bodily shift the propeller.

In witness whereof, I hereunto subscribe

my name this 17th day of December A. D., 1912.

JAMES H. POAGE.
